Primary Examiner — Melanie H Tung*Assistant Examiner* — Fitzgerald L Butac(74) *Attorney, Agent, or Firm* — Panasonic IP Management; Kerry S. Culpepper(57) **CLAIM**

I claim the ornamental design for a robot, as shown and described.

DESCRIPTION

FIG. 1 is a first front perspective view of a robot of the present invention;

FIG. 2 is a second front perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is an end view taken along the line 9-9 in FIG. 3; and, FIG. 10 is a front perspective view in a closed state.

The broken lines showing portions of the robot forms form no part of the claimed design.

1 Claim, 10 Drawing Sheets(56)
